Patented Nov. 16, 1920.

Inventor:

Frank R. Addis.

UNITED STATES PATENT OFFICE.

FRANK R. ADDIS, OF ALLENTOWN, PENNSYLVANIA.

DESIGN FOR A GAME-BOARD.

56,575.

Specification for Design.

Patented Nov. 16, 1920.

Application filed May 8, 1920. Serial No. 379,999. Term of patent 14 years.

To all whom it may concern:

Be it known that I, FRANK R. ADDIS, a citizen of the United States, residing at Allentown, in the county of Lehigh and State of Pennsylvania, have invented a new, original, and ornamental Design for Game-Boards, of which the following is a specification, reference being had to the accompanying drawing, forming part thereof.

The figure is a plan view of a game board showing my new design.

I claim:

The ornamental design for a game board, as shown.

FRANK R. ADDIS.
